BLOCK MOLDING MACHINE

James W. Briscoe, Los Angeles, Calif.

Application December 19, 1945, Serial No. 635,958

5 Claims. (Cl. 25—84)

This invention relates to a machine for molding concrete blocks and has particular reference to hydraulic operating means for such machine.

It is the general object of my invention to provide a machine of the class referred to in which the operations of compressing the charge in the mold and of subsequently expelling the compressed block are effected by means of hydraulic pressure devices.

These and other objects of the invention will be apparent from the following detailed description and by referring to the accompanying drawings, of which:

Fig. 1 is a front elevational view, a device embodying the invention;

Fig. 2 is a sectional view of the device taken substantially through the center thereof;

Fig. 3 is an end view of the device with parts thereof broken away for the sake of clearness;

Fig. 4 is a sectional plan view of the device taken substantially on line 4—4 of Fig. 2, in the direction of the arrow;

Fig. 5 illustrates the finished concrete block; and

Fig. 6 is a plan view of one of the plates used in expelling the compressed block from the mold and for supporting the block during the subsequent removal and drying periods.

The structure of my invention, in the form illustrated in the drawings, comprises side frames 1, 2, to which a top plate 3 is rigidly secured, as by means of bolts 4. The mold of the invention is secured to the top surface of this plate and it takes the form of a rectangular box 5, within which a series of rectangular cores 6, 7, 8 are vertically placed. These cores may form part of the box or they may be anchored on the top plate 3 as by means of bolts 9, and they constitute the cavities of the finished blocks.

A lid 10 is mounted to swing on a pivot 11 of the box and a plate 12 is fastened to this lid to rest snugly against the upper surface of the box when the cover thereof is closed. It is noticed that rows of ribs 13, 14 project from this plate in alignment with the cavities between the cores, the upper surfaces of which are shown grooved at 15, 16 to receive these ribs. Suitable means is provided for tightly locking the lid in closed position on the box, and such means may comprise a series of latch members 17 which are pivotally mounted in position on the lid at 18 to grip the flange 5a of the box when the lid is closed. In order to insure a tight joint, it is well to mount adjusting screws 19 in each latch member.

There are provided with each machine a great number of interchangeable plates or trays 20, each of which is shaped to slide over the cores 6, 7, 8 of the mold and to come to rest on the bottom of the mold. Such tray is, in Fig. 6, shown formed with rows of indentations 20a, 20b in ver-

tical alignment with the ribs 13, 14 of the cover plate. It should be apparent that the ribs 13, 14 will form pockets in the top surface of the finished block and that corresponding ribs will be formed in the pockets 20a, 20b to project from the bottom surface of the blocks. Also that these elements will serve to interlock blocks as they are mounted on top of each other to form the walls for which the blocks are intended to be used.

Concrete is poured into the mold until completely filled, whereupon the cover thereof is closed. Pressure is then applied to raise the bottom plate 20 sufficiently to compress the charge within the mold, and this is done in the following manner. A frame 30 interconnects the side frames 1, 2 to support a box-shaped casing 31, having a closed top 31a, on which a rectangular plate 32 normally rests. This plate is perforated at the four corners thereof to receive stems 33, 34, the upper ends of which extend through perforations of the top plate 3 and abut the bottom surface of the removable bottom plate 20. The lower ends of these stems are shown threaded to receive clamping nuts 34 for correct vertical adjustment of the stems.

The side plates 31a, 31b of the casing 31 are transversely grooved to receive a guide 35, comprising parallel side members 35a, 35b anchored in said grooves. Plates 36, 37 tie these members rigidly together at both ends thereof, and the plate 37 serves to support a cylinder 38, within which a piston 39 is mounted for reciprocating movement. The piston rod 40 is shown rigidly connected to a cross bar 41, which is fitted to slide within a longitudinal slot 35c of each guide member. The ends of this cross bar are turned down to form pivots 41a, 41b on which arms 42, 43 are rotatably hung. The lower ends of these arms are hung on studs 44, 45 of the frame 30. A second pair of arms 46, 47 are hung on the frame 30, at the other end thereof on horizontally aligned studs 48, 49 to support at their upper ends rollers 50, which also ride in the guide slot 35c. Bars 51, 52 interconnect the upper ends of the two sets of arms, substantially as indicated in the drawings.

Fluid under pressure, from a suitable source (not shown) enters a valve 60 at 61 to flow through a passage 62 of the valve stem and a flexible hose 63 to the space within the cylinder 38 ahead of the piston 39, causing the latter to advance. Since the piston rod is rigidly combined with the cross bar 41, and the latter is operatively connected with the arms 42, 43, 46 and 47, it follows that all these parts advance together. Furthermore that, because the lower ends of the arms are pivotally fixed on the stationary frame 30, it is seen that limited vertical movement thereby is imparted to the slide 35 and the casing 31 which supports the slide. The movement of the

casing 31, in turn, imparts vertical movement to the plate 32 and the stems 33, 34, thereby to elevate the bottom plate 20 within the mold and thereby to compress the charge therein. By placing a threaded nut 53 on the piston rod 40 and adjusting its position thereon, it is possible to vary the stroke of the piston and so to increase or diminish the pressure against the charge within the mold. This is an important feature of the invention. A check nut 54 is added to lock the nut 53 in adjusted position.

The cover 10 may now be swung into open position, whereupon the stem of a valve 65 is turned clockwise from the position indicated in Fig. 2 until the passage 66 thereof interconnects the intake opening 67 with a pipe 68, which extends from the valve to the bottom of a vertically disposed cylinder 69. Pressure of fluid from the above named source now enters this cylinder to push the piston 70 thereof upward. A piston rod 71 rises from the piston to the plate 32, in which it is rigidly anchored, the result being that the rising piston rod carries the plate 32 and the stems 33, 34 upward, thereby to push the bottom plate 20 and the charge of concrete upward through the open mold to the very top thereof. The operator thereupon lifts the plate 20 away from the mold and carries it, with the completed block thereon, to a curing and drying rack.

The valve 65 is now returned to the position of Fig. 2, causing the pressure fluid to flow through a pipe 72 to the upper end of the cylinder 69 positively to return the piston 70 and the parts carried thereby to the initial positions of these parts, at the same time forcing the pressure fluid below the piston through a discharge connection 64 back to its source. Finally, the stem of the valve 60 is turned clockwise to connect the intake thereof, through the passage 62, with a flexible hose 59 to carry the pressure fluid behind the piston 39 to return the piston to its initial position, thereby again lowering the casing 31.

When the valve 60 is so turned, it is noticed that a second passage 57 of the stem of the valve 60 connects the hose 63, which is not carrying the inflowing pressure fluid, with a discharge pipe 75, thereby to permit the piston 39 to be moved by the pressure fluid. This discharge pipe may also return the fluid to the common pressure source. The mold is now reset in position to receive a new charge of concrete, upon first placing another bottom plate 20 therein.

I claim:

1. In a concrete block molding machine, a stand, a mold on said stand open at the top to receive a concrete mixture, a compression member seatable on the bottom of said mold, a plate below the mold parallel with said member, studs rising from said plate to the underside of the member, a casing vertically movable within the stand, transverse guides on said casing, a slide movable within said guides, a cylinder on one end of said guides, a piston in said cylinder rigidly connected with said slide, arms hung on the stand and pivotally connected with the slide, and means carrying pressure fluid to said cylinder to move said piston and slide thereby to swing said arms and so to move the casing and plate vertically.

2. In a concrete block molding machine, a stand, a mold on said stand open at the top to receive a concrete mixture, a compression member seatable on the bottom of said mold, a plate below the mold parallel with said member, studs rising from said plate to the underside of the member, a casing vertically movable within the

stand, transverse guides on said casing, a slide movable within said guides, a cylinder on one end of said guides, a piston in said cylinder rigidly connected with said slide, arms hung on the stand and pivotally connected with the slide, means carrying pressure fluid to said cylinder to move said piston and slide thereby to swing said arms and so to move the casing and plate vertically, and a valve controlling the flow of pressure fluid to one end of the cylinder to the other, thereby positively to raise or lower the casing and plate.

3. In a concrete block molding machine, a stand, a mold on said stand open at the top to receive a concrete mixture, a compression member seatable on the bottom of said mold, a plate below the mold parallel with said member, studs rising from the said plate to the underside of said member, a casing vertically movable within said stand, a slide transversely movable in said casing, means on the casing for moving said slide, connections from the slide to the stand for translating transverse movement of the slide into vertical movement of the casing thereby to elevate said plate and member, and hydraulically actuated means for further elevating the plate and member to expel the molded block.

4. In a concrete block molding machine, a stand, a mold on said stand for receiving the concrete mixture, a compression member at the bottom of said mold, a casing mounted for vertical movement within the stand, a slide transversely movable within said casing, hydraulic means including, a cylinder on the casing, a piston having its rod rigidly secured to said slide, connections from the slide to the stand for translating transverse movement thereof into vertical movement of the plate and member, means for adjusting the movement of the piston and the slide, hydraulically actuated means for further elevating the member to expel the molded block, and valve means positively controlling said vertical movement of the plate and the member.

5. In a concrete block molding machine, a stand, a mold on said stand, a compression member seatable on the bottom of said mold, the mold being adapted to receive a plastic charge, a cover for the charged mold, a plate below said mold, elements rising from said plate to the underside of said member, a cylinder vertically mounted on said stand, a piston in said cylinder having a piston rod anchored in said plate, hydraulic means for elevating said plate and member sufficiently to compress the plastic charge within the mold, and at the same time elevating the piston within said cylinder, conduits carrying pressure fluid to said cylinder further to elevate the piston and the plate upon opening said cover thereby to expel the member to carry the charge from the mold, a valve controlling said plastic charge compressing means, and a valve in said conduits controlling flow of pressure fluid to the top and bottom of said piston.
